UNITED STATES PATENT OFFICE

HARMON F. FISHER, OF LONG BEACH, CALIFORNIA, ASSIGNOR TO PETROLEUM RECTIFYING COMPANY OF CALIFORNIA, OF LOS ANGELES, CALIFORNIA, A CORPORATION OF CALIFORNIA

APPARATUS FOR CONVERTING COMMERCIAL FREQUENCY CIRCUITS INTO HIGH FREQUENCY CIRCUITS

Application filed September 3, 1927, Serial No. 217,498. Renewed October 10, 1931.

My invention relates to dehydrators for separating water from petroleum emulsions. Petroleum often becomes associated with water and is converted into an emulsion. Before the petroleum is of any commercial value it must have the water content thereof reduced to two per cent or less. Dehydration is commonly accomplished by passing the emulsion through an electric dehydrator. Such a dehydrator consists of a shell or tank in which a grounded and a live electrode are supported, there being a treating space provided between these electrodes. Means is provided whereby an electric field may be set up in the treating space. The oil in passing through the treating space is subjected to the action of the electric field and the water particles are coalesced so that they will precipitate from the oil. Tests have indicated that emulsion which is ordinarily hard to treat may be efficiently dehydrated by subjecting it to an electric field produced by a high frequency current.

It is accordingly one of the objects of this invention to provide a method in which emulsion is subjected to an electric field produced by a high frequency potential.

Another object of the invention is to provide an apparatus for conducting this method.

A still further object of the invention is to provide an apparatus for converting commercial frequency current into high frequency current.

Other objects and advantages of the invention will be made evident hereinafter.

Referring to the drawings in which I illustrate the invention:

Fig. 1 is a diagrammatic view illustrating the apparatus of the invention in totality.

Fig. 2 is a diagram showing the commercial frequency and the frequency when it has been converted into a high frequency current.

Referring to the drawings, 11 is a dehydrator having a shell 12, a grounded or primary electrode 13, and a secondary or live electrode 14, there being a treating space 15 provided between these electrodes. The dehydrator 11 is only one of many forms of

dehydrators which may be used, and it should be understood that I do not wish to limit myself by the dehydrator shown. The numeral 17 in the upper left-hand corner of Fig. 1 represents a transformer having a 55 primary winding 18 and a secondary winding 19. The transformer 17 is a common type of step-up transformer and the primary winding thereof is fed by a commercial frequency current. Connected to the secondary winding 19 is a primary feed line or primary conductor 20 and connected to the opposite part thereof is a secondary feed line or secondary conductor 21. Connected across the terminals of the secondary winding 19 is a 60 condenser 22.

My invention provides a converter which has a primary mechanism 25 and a secondary mechanism 26. The primary mechanism 25 has a primary contact member 27 and a secondary contact member 28. These primary and secondary contact members are annular and are juxtaposed. The primary contact member 27 has primary fingers 29 which project toward the secondary contact member 28, 75 and the secondary contact member 28 has secondary fingers 30 which project toward the primary contact member 27. The primary and secondary fingers 29 and 30 are offset and overlap as shown. The primary and 80 secondary contact members are supported by insulators 32 as shown. The primary contact member 27 is connected by a conductor 33 to the primary or grounded electrode 13, this connection being made through the shell 85 12. The secondary contact member 28 is connected by means of a conductor 34 to the secondary or live electrode 14. Extended concentrically through the primary and secondary contact members 27 and 28 is a shaft 90 36 which carries a contact maker 37. The contact maker 37 is adapted to engage the primary and secondary fingers 29 and 30 alternately as the shaft 36 is rotated. The shaft 36 is electrically connected to the primary feed line 20 by means of a sliding contact 38 and a contact ring 39.

The secondary mechanism is of the same construction as the primary mechanism and may be described as follows: It has a primary 100

contact member 40 and a secondary contact member 41. The primary and secondary contact members have primary and secondary fingers 42 and 43 which are offset and which overlap as illustrated. The contact members 40 and 41 are annular as in the case of the primary mechanism 25. They are supported by insulators 45. The primary contact member 40 of the secondary mechanism 26 is connected to the primary or grounded electrode 13 by means of a conductor 46 which is connected to the conductor 33. The secondary contact member 41 is connected to the secondary electrode 14 by a conductor 47 which is connected to the conductor 34. Extending concentrically through the primary and secondary contact members of the secondary mechanism 26 is a shaft 49 carrying a contact maker 50, this contact maker 50 being adapted to alternately contact the primary and secondary fingers 42 and 43 when the shaft 49 is rotated. The shaft 49 is in electrical connection with the secondary feed line 21 by means of a sliding contact 51 and a contact ring 52.

The shafts 36 and 49 are preferably in alignment and connected together such as by an insulation portion 53 so that they may be synchronously operated. It should be understood that it is not absolutely necessary that this alignment be made, since the shafts may be connected together by belting or gearing. The shafts 36 and 49 are so connected together that when the contact maker 37 engages a primary finger 29 the contact maker 50 engages a secondary finger 43 and vice versa.

The operation of the apparatus is substantially as follows:

40 The transformer is energized so that a high potential induced current is set up in the secondary winding 19. The wave form of this current is shown by a sine wave 60 in Fig. 2. The shafts 36 and 49 are driven by a suitable means, not shown, and the contact makers 37 and 50 alternately engage primary and secondary fingers of their respective mechanisms. When the contact makers 37 and 50 are in the position shown by full lines 50 in Fig. 1, the primary feed line 20 is connected to the primary electrode 13. This is because of the fact that the contact maker 38 of the primary mechanism 25 is in mechanical contact with one of the fingers 29 of the primary contact member 27. The secondary feed line 21 is at this time connected to the secondary electrode 14. This is because of the fact that the contact maker 50 is in contact with one of the fingers 43 of the secondary contact member 41. A primary circuit is thus completed. As the shafts 36 and 49 rotate, the contact 37 is moved into engagement with a finger 30 of the secondary contact member 28, and the contact maker 50 is moved into engagement with a finger 42 of

the primary contact member 40. At this time the primary feed line 20 is connected to the secondary electrode 14, and the secondary feed line 21 is connected to the primary electrode 13, thus completing a secondary 70 circuit. It will be seen that this change of position of the contact makers 37 and 50 reverses the potential applied to the electrodes of the dehydrator 11. The shafts 36 and 49 are adapted to be driven at a high rate of 75 speed so that for each cycle of commercial frequency the potential applied to the electrodes 14 and 15 is reversed a number of times. Referring to Fig. 2 the wave form shown by dotted lines 61 shows the potential which is produced by the operation of the converting apparatus. It will be seen that in this figure the commercial frequency is increased fourteen fold. The high points of the peaks of each wave of the high frequency 85 potential vary according to its position with respect to the commercial frequency, being limited by the wave form, the cyclic variation in intensity being in synchronism with the cyclic variations of the commercial alternating frequency indicated by the wave form 60.

Insofar as very little current passes through the dielectric material, little sparking trouble is experienced at the instant one of the contact makers leaves one of the fingers of the primary or secondary members. The condenser 22 across the secondary 19 of the transformer 17 tends to absorb any surges and further eliminates any sparking between the contact makers and the fingers. The condenser further offers an easy path to the high frequency currents in comparison to the high inductance secondary winding across which it is placed.

105 From the foregoing description it will be seen that I have presented a dehydrating apparatus in which the emulsion is subjected to the action of a high frequency electric field which, as I have stated before, is found to be very effective in treating emulsions. The apparatus shown for converting the commercial frequency into a high frequency is very well suited for its purpose in this invention, as well as in numerous other industrial installations.

110 I claim as my invention:

1. In combination: a source of alternating current electricity; a primary electrode; a secondary electrode, there being a treating space between said electrodes; a primary conductor connected with said source; a primary mechanism for alternately connecting said primary conductor with said primary electrode and then with said secondary electrode; 120 a secondary conductor connected with said source; and secondary mechanism for alternately connecting said secondary conductor with said secondary electrode and then with said primary electrode.

2. In combination: a source of alternating current electricity; a primary electrode; a secondary electrode, there being a treating space between said electrodes; a primary conductor connected with said source; a secondary conductor connected with said source; a primary mechanism having a primary contact member connected to said primary electrode, a secondary contact member connected to said secondary electrode, and a contact maker connected to said primary conductor and adapted to alternately contact said primary and secondary contact members; a secondary mechanism having a primary contact member connected to said primary electrode, a secondary contact member connected to said secondary electrode, and a contact maker connected to said secondary conductor and adapted to alternately contact said primary and secondary contacts of said secondary mechanism; and means for operating said contact makers so that said contact maker of said primary mechanism is contacting the primary contact member thereof when said contact maker of said secondary mechanism is contacting said secondary contact member of said secondary mechanism. 70
- In testimony whereof, I have hereunto set my hand at Los Angeles, California, this 26th day of August, 1927.
- HARMON F. FISHER. 75
- 10 to said secondary electrode, and a contact maker connected to said primary conductor and adapted to alternately contact said primary and secondary contact members; a secondary mechanism having a primary contact member connected to said primary electrode, a secondary contact member connected to said secondary electrode, and a contact maker connected to said secondary conductor and adapted to alternately contact said primary and secondary contacts of said secondary mechanism; and means for operating said contact makers so that said contact maker of said primary mechanism is contacting the primary contact member thereof when said contact maker of said secondary mechanism is contacting said secondary contact member of said secondary mechanism. 80
- 15 20 and secondary contacts of said secondary mechanism; and means for operating said contact makers so that said contact maker of said primary mechanism is contacting the primary contact member thereof when said contact maker of said secondary mechanism is contacting said secondary contact member of said secondary mechanism. 85
- 25 30 35 40 45 50 55 60 65 70 75 80 85 90 95 100 105 110 115 120 125 130
3. A method of treating an emulsion which comprises: generating an alternating potential of primary wave form; breaking said primary potential up into high frequency pulsations of secondary wave form having peaks corresponding in magnitude to the wave form of said alternating potential; impressing said high frequency pulsations on a pair of electrodes; and passing said emulsion through the field set up between said electrodes. 95
4. A method of treating an emulsion which comprises: setting up a high frequency field, the potential across which successively increases with each high frequency oscillation and subsequently decreases in like manner; and subjecting said emulsion to the action of said field. 100
5. A method of treating an emulsion which comprises: setting up an alternating field, the potential across which successively increases with each oscillation, and subsequently decreases successively with each oscillation; and subjecting said emulsion to the action of said field. 105
6. In combination with a source of alternating current: primary and secondary electrodes defining a treating space; a primary conductor connected to one terminal of said source of alternating current; a secondary conductor connected to the other terminal of said source of alternating current, a primary circuit being completed when said primary conductor is connected to said primary electrode and said secondary conductor is connected to said secondary electrode, a secondary circuit being completed when said primary conductor is connected to said secondary electrode and said secondary conductor is connected to said primary electrode; and means for alternately completing said primary and secondary circuits at a rate greater than the frequency of said source of alternating current. 115
